UNITED STATES PATENT OFFICE.

GUSTAV A. F. AHLBERG, OF PITTSBURGH, PENNSYLVANIA.

CARBURETER.

1,209,652.

Specification of Letters Patent. Patented Dec. 26, 1916.

Application filed March 6, 1914. Serial No. 822,875.

To all whom it may concern:

Be it known that I, GUSTAV A. F. AHLBERG, a citizen of the United States, residing at Pittsburgh, in the county of Allegheny and State of Pennsylvania, have invented certain new and useful Improvements in Carbureters, of which the following is a description, reference being had to the accompanying drawings, forming a part of this specification, in which corresponding numerals of reference in the different figures indicate like parts.

The object of my invention is to provide a carbureter adapted to the use of kerosene or other heavy hydro-carbon oils.

With this purpose in view, my invention consists in providing simple means for initiating the action of said carbureter, providing novel means for utilizing the heat from the motor exhaust to heat carbureting and mixing chambers for vaporizing the fuel after the device is started, in providing novel means for automatically controlling said heat in order to produce uniform and economical results, in providing effective means for producing an initial vaporization to start the motor, and in providing auxiliary or emergency means whereby a portion of the oil fed from the reservoir when the motor is running at slow speed or with a light load, may be diverted in its passage to the mixing chamber and temporarily stored, to be utilized when required for higher speed or greater power;—all of which, with other incidental and novel features, is hereinafter more particularly described and definitely pointed out in the claims.

In the drawings, Figure 1 represents a plan view of my improved carbureter; Fig. 2 is a longitudinal sectional view thereof, taken upon the line 2—, Fig. 1, viewed in the direction of the arrow there shown. Fig. 2^a is a like sectional view forming a part of Fig. 2, being a continuation at the left hand end thereof; Fig. 2^b is a sectional view in plan taken upon the line 2^b—, Fig. 2; Figs. 3, 4, and 5 are vertical sectional views taken upon the lines 3, 4 and 5 respectively, Fig. 2, viewed in the direction indicated by the arrows there shown; and Fig. 6 is a sectional view in plan taken upon the line 6—, Fig. 2.

Referring to the drawings, 1 indicates that portion of a carbureter casing which is at-

tached to the motor, the flange 2 thereon being provided for that purpose. To a flange 3, arranged at right angles to the flange 2, is bolted or otherwise rigidly secured a flange 4, which is integral with an elongated shell 5, the interior of which is cylindrical and is intended to form a carbureting chamber 6. A portion of said shell 5 is provided with a jacket 7, for the purpose hereinafter stated. A main heating case, generally designated by 9, is provided with a flange 10, Fig. 1, which is bolted to a flange 11, formed upon the part 7. The heating case 9 is provided with an opening in the top to which is detachably secured a tight cap 12, preferably protected by means of an asbestos shield 13. Within the shell 9 is a secondary shell 14, Fig. 2, between which and the outer shell is an annular space or chamber 15, for the purpose hereinafter stated. Tapped into an annular flange 16 is a tubular member 17, open at the bottom, but closed at the top, said member being provided with heat radiators 18. A short pipe 19 is connected by means of an elbow 20, with the pipe 17. Said pipe 19 is adapted to connect with the motor exhaust so as to receive therein the heated products of combustion. Tapped into the bottom of the casing 9 is a plug 21, Fig. 2, having a conical end, the apex of which coincides with the axis of the tube 17, the purpose of said plug being to regulate the size of the discharge opening from the bottom of said tube. The discharge from the tube 17 enters the annular space 15, which is in communication by means of a semi-annular passage 22, with an annular chamber 23, in the jacket 7. Said chamber in turn is in communication with an exhaust opening 24.

The heating space between the radiating member 17 and the inner wall 14 of the jacket 9, as well as the annular space between the casing 5 and the pipe 25, is in communication with the outer atmosphere through a passage 24, Figs. 2 and 2^b, the effective opening to which is controlled by means of a sliding gate 24^b, held in place and the effective opening thereof controlled by means of an adjusting screw 24^c.

A metal tube 25 is inclosed within the tubular casing 5, and is arranged concentrically therewith. One end of said tube is in communication with the tube 17, through an elbow 26, formed upon the latter, while the

other end is incased within a hollow plug 27, Figs. 1, 2 and 2^a, which is tapped into a flanged bore in the casing 1. Said plug is provided with lateral openings 28, to permit an exhaust from the tube 25.

A throttle valve 29, Fig. 2, is pivoted diametrically in the pipe 19, said valve having an actuating arm 30 rigidly attached thereto. A link 31 serves to connect the end of the arm to one arm of an elbow lever 32, pivoted at 33, to a boss 34 in the lower part of the pipe 17. A lever 35 is connected to a pin 36 upon the depending arm of the lever 32. The upper end of the lever 35 is pivoted at 37 to a bracket 38. A rod 39 is located within the tube 25, and has one end pivotally connected at 40, to the lever 35, while the opposite end is centrally tapped as shown at 41, Fig. 2^a, through the plug 27, and provided with a lock-nut 42. The device described comprises a thermostat and is so adjusted that when the carbureter is cold, the valve 29 will be fully open, but when heated the expansion of the rod 39 acting through the levers 35 and 32, and the link 31 and arm 30, will cause the valve to close more or less in proportion to the heat developed from the motor exhaust.

The part 1 of the casing is enlarged in diameter in the direction of the shell 9, as shown in Fig. 2, so as to form a valve-chamber leading to a mixing chamber 43, into which a portion 44 of the casing 5 is extended in the form of a nozzle as shown. A valve 45, having a hub 46, is slidably mounted upon the tubular extension or nozzle 44, and adapted to fit a valve-seat 47, formed in the flange 4. Openings 48, Figs. 2, 3 and 5, are formed in the flange 4 to communicate with the atmosphere. A coiled spring 49 tends to hold the valve 45 normally closed.

Extending through bores in the flange 4, are pins 50, Figs. 1, 2 and 5, which are rigidly attached to the valve 45. A lever 51 is pivoted to a bracket 52 upon the flange 4; said lever having bifurcated arms 53, arranged to engage the pins 50. The opposite end of said lever is in engagement with a spring 54, Fig. 2, which is interposed between it and an adjusting screw 55, which is tapped into a bracket 56, on said casing. The head 57, of said screw is bored out to form a cavity for the reception of the spring, while peripheral grooves 58 are formed in said head to receive a retaining spring 59 upon the end of the bracket 56. By means of the screw 55, the tension of the spring 54 may be adjusted to modify the resistance of the valve spring 49 to any desired degree.

Formed upon one side of the main casing is an oil reservoir 60, having a removable cap 61, which is centrally bored as shown in Fig. 3, to receive and guide a vertical valve-

stem 62, the upper end of which is covered and protected by a removable cap 63. Rigidly attached to said valve-stem is a hub member 64, having a peripheral groove 65 therein which is adapted to receive and engage the short arms of counterweight levers 66, pivoted to lugs 67, upon the cap. A loose float 68 is placed within the reservoir and adapted to lift the counterweights as oil is permitted to enter the reservoir.

The lower end of the valve rod 62 is tapered to form a valve and close an opening 69 in a valve-plug 70, having a central guiding bore in its top for guiding the valve-rod and lateral openings 71, to permit the oil to enter the reservoir. A nipple 72 enables the reservoir to be connected with a supply tank from which a full feed may be received subject to the control of the valve. The features of said device are common and well known, and I make no claim thereto.

An offset 73, Figs. 2 and 3, is formed in the reservoir casing directly beneath the main casing 5. A plug 74 is tapped through the bottom of said offset for the screw-threaded portion of a valve-stem 75, which is tapped therein. A plug 76 in axial alignment with the plug 74, is tapped into the main casing above said offset, so as to extend into the carbureting chamber 6, of the main casing. Said plug is provided with an enlarged feed bore 77, a reduced bore 78, to form the valve seat, and an enlarged bore 79 to form the discharge. The purpose of the latter enlargement will be presently stated. The middle portion of the valve-plug is reduced in diameter as shown, to form an annular chamber 80, into which oil may flow through lateral bores 81. The upper end of the valve plug is passed through a bore in a ring 82, located in the carbureting chamber to form a restricted cross-sectional area so as to increase the suction past the fuel inlet opening as hereinafter described, said opening being made flaring as shown at 83. A hand-wheel 83^a is secured to the valve stem, said wheel having peripheral notches to engage a spring controlled stop 83^b to enable the valve to be adjusted and secured in place.

A horizontal bore 84, Figs. 2 and 4, is arranged to communicate with the annular chamber 80, and also with a lateral bore 85. A hollow plug, generally designated by 86, is tapped into the casing from beneath, the lower portion thereof forming a supplemental or emergency reservoir 87, while the upper portion 88, forms a nipple or discharge nozzle. Said nozzle is provided with a central bore 89, and lateral bores 90, in communication with the passage 85. Bores 91, also lead to the reservoir 87, to permit oil to enter the same from the passage 85, which may be drawn therefrom by suction preferably through a small siphon tube 85^a,

BEST AVAILABLE COP

1,209,652

as and for the purposes hereinafter set forth. Between the main casing 5 and the tube 25, is interposed a tube 92, which is arranged parallel with the tube 25, which latter is grooved as shown at 93 to fit said tube. The tube 92 is open at both ends, one of which is bent downwardly as shown at 94, to receive the nozzle 88, while the other is bent upwardly as shown at 95, into a bore 106, Fig. 2, which is in communication with a small discharge port 97, slightly below but in close proximity to a throttle-valve 98, which is mounted upon a journal 99 supported in bearings in the casing 1 to control the outlet therefrom. This may be actuated by any well known manual or other means not shown. A screw-plug 100 is tapped into a bore 101, in communication with the bore 96, for the purpose of controlling the quantity of fuel mixture which may be delivered to the port 97.

In order to render the carbureter operative for starting the motor, it is desirable that the emergency reservoir 87, as well as the carbureting chamber, should be heated. This I prefer to accomplish electrically. A generator 101, Fig. 2, has one of its terminals connected by a lead 102 with a coil 103, surrounding the reservoir 87, the other terminal 104 of said coil being extended to form a heating coil 105, within the casing 5, being interposed between said casing and a thin copper tube 106. The opposite terminal of the coil 105 is carried by means of a lead 107, shown in Fig. 1, and diagrammatically indicated in Fig. 2, back to the generator, the two coils being connected "in parallel". A switch 108 is interposed in the circuit. I especially recommend that the auxiliary reservoir 87, be made very small with walls as thin as practicable, in order that it may be quickly heated.

The operation of the carbureter is as follows: In starting the device, the switch 108 is closed until the reservoir 87 and the carbureting chamber become heated. The throttle valve 98 is then opened just enough to expose the port 97, while still closing the main passage through the carbureting and mixing chambers. As a result of this adjustment, a strong suction, resulting from the aspiration of the motor, is induced through the port 97, and tube 92, thereby causing a suction through the primary jet 88, openings 90, passages 85, 84, openings 81, and valve opening 77. Fuel is thus drawn from the latter, discharged through the primary jet 88, where it is commingled with the air in the tube 92, and the combustible mixture is, in turn, delivered through the port 97, to the combustion chamber of the motor. As soon as the motor starts, the products of combustion are discharged from the exhaust, a portion thereof

passing directly through the pipe 25 to the openings 28, and a portion passing through the pipe 17 and jackets 15 and 23 respectively, to the discharge 24, thereby serving to heat the entire casing. When this is accomplished, the switch 108 is opened, as 70 is also the throttle valve 98. Upon opening the latter, the suction through the port 97 ceases and is transferred to the main body of the structure, thereby drawing atmospheric air through the passage 24, and the 75 annular heating chamber inclosed by the jacket 9, into contact with the radiating surfaces 18, from whence it passes through the annular space between the main casing and the heating pipe 25, past the throttle valve 80 98, to the motor. On its way it passes the restricted zone formed by the ring 82, thereby producing a strong suction which causes fuel to be drawn from the jet opening 79 into the carbureting chamber 6. The quantity of fuel so drawn is, of course, controlled by the valve 75.

As a result of the suction through the main fuel jet 79, a downward or reverse suction is induced through the primary or 90 starting jet 88, thereby drawing heated air downwardly therethrough, and thence through the bores 90, passages 85 and 84, to the lateral openings 81, in the main jet, where it commingles with the fuel passing 95 upwardly through the discharge bore 79, the upper part of which is enlarged to provide for such additional volume. As oil is conveyed through the main jet, a portion of it tends to flow laterally through the 100 openings 81 into the passage 84, and thence to the bores 91, Fig. 4, through which it enters the reservoir 87. This reservoir is intended as an emergency supply. When the motor is running slowly, or upon a light 105 load, the tendency is to fill the reservoir; but when the speed or load is increased, fuel is drawn therefrom by the increased suction through the passage 84, thereby commingling air and fuel in the bore 79, with 110 the fuel which is drawn from the main oil reservoir, to supplement and aid the action in the carbureting chamber in which heated air drawn through the main heating appliance is commingled with the fuel which is 115 vaporized thereby and conveyed to the mixing chamber 43. Each aspiration of the motor serves to produce a partial vacuum behind the valve 45, which causes it to open and admit atmospheric air to commingle in 120 the mixing chamber with the supply drawn from the carbureting chamber. The volume of air thus admitted may be controlled to the utmost nicety by means of the spring 54, and adjusting nut 55; it being understood that the tension of the spring 49 should be somewhat more than sufficient to 125 normally close the valve and hence any back

pressure caused by the spring 54, and the intervening lever 51, would tend to reduce the closing pressure upon the valve. It will thus be seen that the air and fuel control is 5 automatic, being proportionate to the load and speed of the motor.

It is known that the heat required to raise kerosene to a temperature which will cause it to give out the highest motive efficiency must be closely regulated and maintained within certain limits. Should the heat in the storage reservoir be too low or 10 too high, the excess in either direction will increase the fuel consumption and lessen the accomplished work. It is therefore essential that the controlling factor should be automatic. This is accomplished by 15 means of the thermostat described. The expanding rod 39 is so adjusted by means of the adjusting screws described that when the carburetor is cold, the throttle valve 29 will stand fully open as shown; but as the heat within the pipe 25 is increased, said rod 20 will expand, thereby moving the interposed levers closing the throttle to the desired degree, and proportionately shutting off the supply of heat from both the pipe 25 and the main heating reservoir.

I have found in practice that by following the operation described, a motor may be readily started with kerosene alone and that the combustible mixture is so perfectly blended and so uniform in character as to insure the maximum working efficiency, and 35 that without smoke or odor.

In effect what I have in the example illustrated, termed the carbureting and mixing chambers, constitute one main passage intervening between the air inlet and the discharge outlet, while the tube 92, into which the primary jet discharges constitutes an alternative passage for a like purpose, one or the other of said passages being brought 40 into commission according to the predetermined position of the throttle valve in the outlet passage, it being understood that when the starting jet is used, the carburetor is heated by the electrical current and when the shift is made to the main jet, the heat 45 is intended to be supplied wholly from the motor exhaust.

Having thus described my invention, I claim:—

1. A carburetor having a carbureting 55 chamber, a mixing chamber, said mixing chamber having an outlet adapted to lead to a motor, a separate conduit leading to a discharge port in immediate communication with said outlet, a primary fuel jet leading to said conduit, means for admitting air to said conduit and carbureting chamber, a main fuel jet in communication with said carbureting chamber, a source of liquid fuel supply in communication with 60 each of said jets, an electric heating coil

in a normally open circuit for heating said conduit and a valve located in the outlet of said mixing chamber, said valve being disposed, when slightly opened, to cause a suction to be maintained through said conduit 70 while substantially closing the outlet from said mixing chamber, and when further opened to permit the suction to act upon the mixing chamber, whereby a heated mixture is first drawn through said conduit to 75 start the motor and then through said chambers to continue its operation.

2. A carburetor having in combination therewith a starting device comprising a fuel reservoir, a fuel jet in communication 80 with said reservoir, a conduit leading from the outlet of said jet to a mixture discharge port, said jet being arranged to discharge into the open end of said conduit, means for admitting air around said jet into said 85 open end, a throttle valve located at the outlet of said carburetor, adapted when partially open to subject said discharge port to the suction of a motor while substantially closing the main discharge opening from 90 said carburetor, a source of electricity, an electric heating coil for heating the contents of said fuel reservoir, and means for closing an electric circuit therewith.

3. A carburetor having a carbureting 95 chamber therein for the reception of liquid fuel and air, an air inlet leading thereto, a discharge outlet leading therefrom, a source of liquid fuel supply, a main jet leading therefrom to said chamber, an intervening 100 passage leading from the body of said jet between the inlet and discharge openings thereof to a starting jet, a starting jet, an open-mouthed tube leading therefrom to a port opening into the discharge outlet of 105 said carbureting chamber, to convey commingled fuel and air thereto, a throttle valve in said discharge outlet adapted when in a predetermined partially open position to expose said discharge port to the suction of a 110 motor while substantially closing the outlet from said carbureting chamber, and when in a more open position, to permit a full suction from said discharge outlet, a source of electricity, electrical heating means 115 for heating said fuel and tube, and means for opening and closing said circuit whereby when said circuit is closed and said throttle partially opened, an explosive mixture may be drawn through said starting jet and 120 tube to start a motor and when further opened, the suction may be through said main jet and carbureting chamber.

4. A carburetor having an air inlet and a discharge outlet in combination with intervening alternative carbureting passages one of which is inclosed within the other, with a space between them, a source of liquid fuel supply, two fuel jets in communication therewith, one being arranged 125 130

REST AVAILABLE COP

1,209,652

to discharge into one and the other into the other of said passages, a source of electrical energy, an electrical heating coil arranged to form a lining for the larger of said carbureting passages whereby both may be heated and means located in the discharge outlet of the carbureter for shifting the motor suction from one to the other of said passages.

10 5. A carbureter having an air inlet and a discharge outlet, intervening alternative main and auxiliary carbureting passages in communication therewith, a source of liquid fuel supply, a main fuel jet in communication therewith and with said main carbureting passage, a valve for controlling the same, a continuously open starting jet in open communication with said auxiliary carbureting passage, said starting jet having a branch fuel passage leading thereto from a point in the fuel supply conduit connected with said main jet in advance of said controlling valve, an emergency fuel reservoir in communication with said branch passage, and a valve located in said discharge outlet for shifting the motor suction from one of said carbureting passages to another, whereby when said suction causes a fuel discharge from said starting-
30 jet, fuel may be drawn in said emergency reservoir, as well as to said starting jet and when said discharge outlet valve is reversed, fuel may be drawn from said emergency reservoir through said branch to said main jet to supplement the latter and meet excessive fuel demands.

6. A carbureter having an air inlet and a discharge outlet alternative main and auxiliary carbureting passages, the open fuel and air inlet of the latter being within the body of the former, a source of fuel supply, a valve controlled main fuel jet for delivering fuel therefrom to said main carbureting passage, a starting jet having its discharge end in operative proximity to the inlet of said auxiliary carbureting passage, a branch fuel passage leading to said starting jet from the conduit through which fuel is directly supplied to said main fuel jet, an emergency fuel reservoir in communication with said branch fuel passage and means located in the discharge passage of said conduit for shifting the motor suction from one carbureting passage to the other.

7. A carbureter having an air inlet and a discharge outlet, intervening alternative carbureting passages in communication therewith, a source of liquid fuel supply, a main fuel jet in communication therewith, and with one of said passages, a starting fuel jet in communication with the other passage, said starting fuel jet being in communication with the fuel passage leading to said main jet, electrical means for temporarily heating the walls of said carbureter, means for conveying the heated products of combustion from a motor into proximity to the walls of said carbureter to heat the same after starting, and means located in said discharge outlet for shifting the motor suction from one of said carbureting passages to another whereby when said main jet is in commission, air will be drawn from said starting jet to the fuel passage leading to said main jet.

8. A carbureter having an air inlet and a discharge outlet, intervening alternative carbureting passages in communication therewith, a source of liquid fuel supply, a main fuel jet in communication therewith, and with one of said passages, a starting fuel jet in communication with the other passage, said starting jet being in communication with the fuel passage leading to said main jet, an emergency fuel reservoir in communication with the branch passage leading to said starting jet, electrical means for temporarily heating the walls of said carbureter, means for conveying the heated products of combustion from a motor into proximity to the walls of said carbureter to heat the same after starting, and means located in said discharge outlet for shifting the motor suction from one of said carbureting passages to another, whereby a portion of the fuel drawn from the main fuel reservoir may be diverted to said emergency reservoir and stored for use when an excessive demand is made upon the motor.

In testimony whereof, I have signed this specification in the presence of two subscribing witnesses, this second day of March, 1914.

GUSTAV A. F. AHLBERG.
